UNITED STATES PATENT OFFICE

124,678

DESIGN FOR A COMBINED SACHET PILLOWS AND HOLDER UNIT

Richard C. Jones, New York, N. Y., assignor to Lucien Lelong, Inc., Chicago, Ill., a corporation of Illinois

Application November 18, 1940, Serial No. 96,662

Term of patent 3½ years

To all whom it may concern:

Be it known that I, Richard C. Jones, a citizen of the United States and a resident of the city of New York, in the county of New York and State of New York, have invented a new, original, and ornamental Design for a Combined Sachet Pillows and Holder Unit, of which the following is a specification, reference being had to the accompanying drawing forming a part thereof.

On the drawing:

I claim:

The ornamental design for a combined sachet pillows and holder unit, as shown.

RICHARD C. JONES.
